United States Patent

Des. 239,820
Patented May 11, 1976

239,820

SAMPLING PROBE

Rowland Retrum, St. Louis, Mo., assignor to Ralston
Purina Company, St. Louis, Mo.

Filed Sept. 18, 1974, Ser. No. 503,823

Term of patent 14 years

Int. Cl. D10—99

U.S. Cl. D10—46

FIG. 1

FIG. 2

FIG. 1 is a perspective view of a sampling probe embodying my new design;
FIG. 2 is a side elevational view thereof;
FIG. 3 is a top plan view thereof; and
FIG. 4 is a bottom plan view thereof.
I claim:
The ornamental design for a sampling probe, substantially as shown.
